UNITED STATES PATENT OFFICE.

JOSEPH COURVILLE, OF DETROIT, MICHIGAN, ASSIGNOR TO FARRAND ORGAN COMPANY, OF DETROIT, MICHIGAN, A CORPORATION OF MICHIGAN.

RELIEF-VALVE.

SPECIFICATION forming part of Letters Patent No. 687,497, dated November 26, 1901.

Application filed August 7, 1901. Serial No. 71,204. (No model.)

To all whom it may concern:

Be it known that I, JOSEPH COURVILLE, a citizen of the United States, residing at Detroit, in the county of Wayne and State of Michigan, have invented certain new and useful Improvements in Relief-Valves, of which the following is a specification, reference being had therein to the accompanying drawings.

10 The invention relates to relief-valves, and is especially adapted for use in connection with foot-actuated wind-pumps of cabinet-organs or pneumatic self-playing attachments for pianos. Heretofore instruments of this kind have been provided with relief-valves which have usually been connected with a store-bellows or pressure-regulator.

The objects of the valve are, first, to guard against the development of too-great pressure 20 acting upon the reed or sound-producing devices, and, second, to relieve the resistance to the pressure of the foot upon the pumping-pedal when the bellows is fully collapsed. The latter object is of greater importance in 25 self-playing attachments for musical instruments in which an increased pressure will do no harm; but the resistance to the depression of the pedal will increase the effort of the performer. In the present invention this object is more perfectly accomplished by placing the relief-valve in direct connection with the pumping-bellows instead of the indirect connection through the store-bellows heretofore used.

30 In the drawings, Figure 1 is a front elevation showing the pumping-bellows and a portion of the store-bellows of an instrument. Fig. 2 is a cross-section therethrough. Fig. 3 is an enlarged section of a portion of Fig.

40 2, showing the parts in a different position.

A is a pumping-bellows of any ordinary construction, which is shown as mounted on a stationary inclined board B, also forming the support for the store-bellows C. The bellows A is actuated by connection with the pedal and is adapted to exhaust the air from the store-bellows C, causing the latter to collapse against the tension of the spring D. The air passes from the bellows C into the bellows 45 50 A through valve-controlled ports E in the

board B, and the movable front board of the bellows A is also provided with valve-controlled ports F.

G is the relief-valve which forms the subject-matter of the present invention. This 55 may be arranged in any position in proximity to the bellows A, but as shown is arranged below the lower hinged edge of said bellows.

H is the port controlled by the valve, which, as shown, is formed in the board B and connects directly with the space within the bellows.

The precise construction of the valve G is immaterial; but a simple and effective arrangement is formed by the bar a, having a 65 hinge b at one edge formed of flexible material. The face of this bar normally covers the port H, which may be single or a series of apertures, as shown. The valve is normally held closed by gravity and by the suction of 70 the bellows A and is permitted to remain in this position until the store-bellows C is almost completely collapsed. For then opening the valve a lug or projection I upon the movable member of the store-bellows is arranged 75 to impinge against an arm J, projecting from the valve G, so as to force said valve from its seat and open the ports H. When this is accomplished, air will pass directly through the port H into the bellows E and will thereby relieve all resistance to the pedal K excepting 80 that of the spring for returning the movable board of the bellows.

The principal advantage of the construction is the directness of the relief connection with 85 the bellows A, and a further advantage is that the valve may be more conveniently placed as shown than upon the movable board of the store-bellows.

What I claim as my invention is—

1. The combination with a wind-pump and a store-bellows connected therewith, of a relief-valve normally closing a direct atmospheric connection with said pumping-bellows adapted to be opened by the abnormal movement of said store-bellows. 95

2. The combination with a suction wind-pump and a store-bellows connected therewith, of a relief-valve normally closing a direct atmospheric connection with said pump- 100

ing-bellows and means for opening said valve upon the collapsing of said store-bellows.

3. The combination with a stationary board having a pumping-bellows mounted upon one side thereof and a store-bellows upon the opposite side thereof, of a valve seated upon said board adjacent to said pumping-bellows and normally covering a port in the former connecting with the latter and an arm connected to said valve projecting into the path

of a coöperating shoulder on the movable member of said store-bellows, whereby the collapsing of the latter will actuate said valve and open said port.

In testimony whereof I affix my signature **15** in presence of two witnesses.

JOSEPH COURVILLE.
